UNITED STATES PATENT OFFICE.

SYLVESTER L. JOINER, OF MONROE, LOUISIANA.

LANTERN-BRACKET AND FLAG HOLDER.

1,246,749.

Specification of Letters Patent. Patented Nov. 13, 1917.

Application filed April 14, 1917. Serial No. 162,007.

To all whom it may concern:

Be it known that I, SYLVESTER L. JOINER, a citizen of the United States, residing at Monroe, in Ouachita parish and State of 5 Louisiana, have invented certain new and useful Improvements in Lantern - Bracket and Flag Holders, of which the following is a specification.

This invention relates to an improvement 10 in lantern bracket and flag holders and is designed especially for the use of railways in holding lanterns and signal flags on the rear of trains, or at other points where such signals should be displayed.

15 Practically all roads are at present using a bracket for holding the lantern which bracket slips into a holder secured to the sides of passenger cars and freight cabooses, these holders being so placed that they can 20 be readily reached from the platform, and there are usually four to each car. An objection to these holders is that at present the weight of the bracket is the only means for holding it in position, and it is liable to be 25 jarred out of position, especially on sudden stoppage of the car.

My invention improves this present form by providing means for positively locking the bracket in the holder and to also aid in 30 wedging the flag stick in so that it will not be liable to become loosened by wind.

My invention consists in the novel features of construction hereinafter described, pointed out in the claims, and shown in the accompanying drawings, in which:—

Figure 1 is a plan view of the bracket and holder.

Fig. 2 is a plan view of the holder with bracket removed.

40 Fig. 3 is a vertical section through the holder and locking pin, the bracket being in section.

Fig. 4 is a section at right angles to Fig. 3.

In the drawings 1 designates a bracket 45 having a shank portion 2 provided with a slot 3 and a wedge shaped flange 4 carried at the outer end of the shank. The bracket holder comprises a plate 5 having a vertical undercut groove or channel 6 to the lower 50 portion of which is connected a vertical, slightly tapering sleeve 7.

In one side wall of the sleeve is formed a pin receiving opening 8 and in the opposite wall a threaded opening 9, of greater 55 diameter than the opening 8.

A sleeve 10 open at its inner end is threaded into the opening 9 and contains a spring 11. A pin 12 passes through a suitable perforation in the outer closed end of the sleeve 10 and is provided with a cap 13 60 on its outer end and with a collar 14 which works in the sleeve 10. The spring 11 bears at one end on the end of the sleeve 10 and at the other end on the collar 14.

In use the pin is drawn outwardly by 65 means of the cap 13 and the bracket fitted into place the flange 4 entering the groove or channel 6. The pin is then released and passes through the slot 3 of the shank and into the opening 8 of the sleeve 7, thereby 70 preventing removal of the bracket from the holder without first drawing the pin outwardly.

The sleeve 7 also is adapted to receive and hold the flag stick, said stick being notched 75 as indicated at 15, and when inserted it straddles the pin and is held more securely than it otherwise would be.

One special advantage of the present invention is that it can be adapted to the 80 present brackets and holders now in use so that it is unnecessary for the railroads to discard any present equipment, or to purchase entirely new parts in order to adopt the invention.

85 This is of considerable importance as the availability and commercial value of an invention often depends on the economy with which it can be adopted. The sleeve is notched at 7^a to receive the shank. 90

What I claim is:—

1. A device of the kind described comprising a slotted bracket and a notched flag stick, of a holder comprising a sleeve mounted vertically and adapted to receive the 95 bracket or the stick, said sleeve having a pin receiving opening in one wall, a second sleeve threaded into the opposite wall of the first mentioned sleeve, a headed pin working through the last mentioned sleeve, 100 and having a collar working in said sleeve, and a spring arranged in the second mentioned sleeve and bearing on said collar, said pin being adapted to pass through either the slot of the bracket or the notch of the 105 stick, as and for the purpose set forth.

2. A holder of the kind described comprising a flat plate having a channel formed vertically thereon and a sleeve carried by the lower portion of the plate and commun- 110

cating with the channel, said sleeve being adapted to receive a suitable light or signal support, one side of said sleeve adjacent the channel being perforated, and the opposite side having a threaded opening, a second sleeve threaded into said opening and in alinement with the perforation, a spring in

the last mentioned sleeve, and a pin working through the last mentioned sleeve and transversely across the first mentioned sleeve 10 and pressed by said spring into said perforation, as and for the purpose set forth.

In testimony whereof I affix my signature.

SYLVESTER L. JOINER.
